UNITED STATES PATENT OFFICE.

ERNEST HENRY VORDTRIEDE, OF ST. LOUIS, MISSOURI.

CAR-COUPING.

SPECIFICATION forming part of Letters Patent No. 650,920, dated June 5, 1900.

Application filed February 19, 1900. Serial No. 5,753. (No model.)

To all whom it may concern:

Be it known that I, ERNEST HENRY VORDTRIEDE, a citizen of the United States, residing at St. Louis, State of Missouri, have invented certain new and useful Improvements in Car-Couplers, of which the following is a full, clear, and exact description, reference being had to the accompanying drawings, forming a part hereof.

10 My invention has relation to improvements in car-couplers; and it consists in the novel arrangement and combination of parts, more fully set forth in the specification and pointed out in the claims.

15 In the drawings, Figure 1 is a combined top plan and sectional plan of my device, the chains being removed. Fig. 2 is a combined side elevation and middle sectional elevation showing one side coupled and the other un-coupled and corresponding in this respect to the parts shown in Fig. 1, this figure showing the end wall of the car in dotted outline; and Fig. 3 is a side elevation of one of the couplers with the pin in its coupled position, the link being shown partly broken away.

20 The object of my invention is to construct a car-coupler which will be simple, cheap, and durable, one containing a minimum number of parts, one which will be positive in action, and one which shall automatically couple the cars irrespective of any difference in the level between the cars to be coupled.

25 In detail the device may be described as follows:

30 Referring to the drawings, 1 represents the draw-bar, and 2 the draw-head, of the coupler, the same being mounted on the car in any approved manner. Pivoted to the rear of the draw-head and adapted to swing in a vertical plane is a bent lever 3, the long arm of which passes through an elongated opening 4 in the top wall of the draw-bar, the said arm being provided with an eye 5, to which is secured one end of a chain 6, whose opposite end is secured to a lug 7, carried by a rock-shaft 8, mounted in brackets 8' on the car and provided with a handle or lever 9 on either end on the outside of the car. The short arm 3' of the lever 3 is received by a pocket 10, (having a rear inclined wall 10'), formed in the bottom wall of the draw-bar, the free end of said short arm being rounded

for a purpose which will presently be obvious. The free end of the lever terminates in a downwardly-projecting slightly-curved rigid arm or coupling-pin 11, which when in its lowest position engages the coupling-link 12, carried by the opposite draw-head. The open mouth of the draw-head flares both vertically and horizontally to allow the necessary freedom of movement to the link under all conditions and to guide the same into either mouth during the coupling operation.

Movably mounted in each draw-bar forward of the pivotal pin of the lever 3 and partially supported by a pin 12', disposed parallel to the pivotal pin of the lever 3, is a tripping-block 13, the limits of whose movements are defined by the ends of the elongated slots 14, formed in the vertical walls of the draw-bar and receiving and guiding the ends of the pin 12'.

By drawing on the chain 6 (which may be accomplished by turning the crank or lever 9, so as to turn the shaft 8 in the proper direction to pull on said chain) the lever 3 will be raised and the pin 11 disengaged from the coupling-link 12. (See the right of Fig. 2.) By this movement the rounded end of the short arm 3' will force the block 13 outwardly a distance determined by the length of the slots 14, in which the pin 12' is guided. The frictional resistance of the rock-shaft will keep the pin 11 (which forms a part of the lever 3) disengaged. If now the opposite car approaches the one in which the coupling-pin 11 is disengaged, the link carried by said car will push against the block 13, forcing it inwardly, as seen by the arrows, Fig. 2, the block in turn engaging the arm 3', thereby tripping the lever, as shown by the arrows, and forcing the pin 11 to engage the link by which the impact was produced. The end of the block 13 will come squarely against the arm 3', and when once the pin is coupled it cannot become uncoupled until the rock-shaft is turned in the proper direction to disengage the pin from the link. The pin 11 plays in the openings 15 15, formed for its reception in the upper and lower walls of the draw-bar. In raising the lever 3 to disengage the pin 11 the arm 3' of course forces the block 13 outwardly, as stated; but to prevent binding of the parts under the circumstances the arm

3' is made rounded, being that the lever describes the arc of a circle in ejecting the said block.

As seen from Fig. 2, the coupling may be effected even if the draw-heads are on different levels. When the lever 3 and pin 11 are in their lowest positions, it is apparent that the force of the impact from which the coupling resulted is taken up not only by the pivotal pin, which carries the lever 3, but by the pin 12', carrying the block 13. This arrangement prevents too great a strain coming on the pivotal pin of the lever and preserves the same against bending or weakening.

Having described my invention, what I claim is—

1. A car-coupler comprising a draw-head, a lever pivoted rearwardly thereof and swinging in a vertical plane, a curved coupling-pin or arm rigidly secured to said lever, a movable block mounted in front of the lower arm of the lever but disconnected therefrom, said block being adapted to be struck by the link of the opposite coupler and thereby force the coupling-pin into said link, substantially as set forth.

2. A car-coupler comprising a draw-bar and draw-head, the mouth of the latter flaring

both vertically and horizontally, a bent lever pivoted to swing in a vertical plane mounted in the draw-bar, the long arm of the lever projecting above the upper wall of the draw-head, and the short arm being received by a pocket in the lower wall, said pocket having a rear inclined wall, a curved coupling-pin or arm rigidly carried by the long arm of the lever and adapted to pass through openings formed in the lower and upper walls of the draw-head, a block mounted in the draw-bar in front of the lever but disconnected therefrom, and having a supporting-pin the outer ends of which are mounted in elongated slots formed in the side vertical walls of the draw-bar, the block being adapted to be struck by the link of the opposite coupler and trip the lever to a locked position, and means for raising the lever and pin sufficiently to disengage the latter from the link for purposes of uncoupling, substantially as set forth.

In testimony whereof I affix my signature in presence of two witnesses.

ERNEST HENRY VORDTRIEDE.
